HENRY J. RIES, OF IOWA CITY, IOWA

GRAVITY RIGHT-OF-WAY TRAFFIC SIGNAL

Application filed March 3, 1930. Serial No. 432,753.

My invention relates to signal means and more particularly to signal means for use in the control of traffic, and it consists in the constructions, combinations and arrangements of parts herein shown and described.

An object of my invention is to provide a signalling device for use in the control of traffic at intersections, which is automatically operable upon the approach of vehicles to 10 said intersection to signal such approach to on-coming vehicles in other directions and to signal such approach to pedestrians.

A further object of my invention is to provide a device of the type described which will 15 give both a visual and audible signal to vehicles approaching in other directions and will further indicate to said other vehicles a direction in which the on-coming vehicle is approaching.

20 A further object of my invention is to provide a device of the character described which is simple to manufacture, has few parts and does not get out of order easily.

Other objects and advantages will appear 25 as the specification proceeds and the invention will be more particularly defined in the appended claims.

The device is illustrated in the accompanying drawings forming a part of this application, in which:

Figure 1 is a top plan view of the signal system set up for operation;

Figure 2 is a sectional view on line 2—2 of Figure 1;

35 Figure 3 is an elevational detail view of a portion of the device;

Figures 4 to 7, inclusive, are transverse sectional views on lines 4—4 to 7—7, inclusive, of Figure 2;

40 Figure 8 is a sectional view on line 8—8 of Figure 1;

Figure 9 is a sectional detail view of a portion of the device;

45 Figures 10 to 12, inclusive, are prospective detail views of portions of the device.

In carrying out my invention I make use of any ordinary intersection, generally indicated at 1, between intersecting streets 2 and 3. At the center of this intersection I provide a signal tower 4 adapted for housing

and mounting the various signals of my device. It is obvious that the signal tower could be placed at any other desired point and that the device could be utilized at any other place other than at intersections of 55 streets. This signal tower 4 is adapted and positioned to control the vehicle traffic approaching the intersection.

Suitable signal means indicated at 5 are provided for the control of pedestrian traffic 60 on the sidewalks 6 adjacent the street. A detailed description of these signalling devices will be given hereinafter.

For warning visually as well as audibly 65 oncoming vehicles of the approach of a vehicle, the tower 4 is equipped with a lamp 7 which may be of any suitable construction and which may be mounted in any desired manner in the tower but which is shown as mounted at the vertical as well as the trans-

verse center thereof and a bell 8 or other audible signal positioned as desired but shown as placed at the top of the tower and substantially at the transverse center thereof. As appears most clearly in Figure 6 this lamp is adapted to project its rays in four directions through the tubes 9 which establish communication with the windows 10. It is obvious that if the signal system is used 70 at an intersection consisting of more or less than two intersecting streets that more or less of the windows 10 and communicating tubes 9 could be provided to fit this situation.

It is only necessary that communication be had between the light and each of 75 the streets approaching the intersection. The bell as appears most clearly in Figures 2 and 3 is placed on top of the main portion of the tower and is unobstructed by the walls thereof.

For covering and uncovering the windows 10 which communicates with the lamp 7 for rendering the light signal operative and inoperative and for indicating the direction of 80 approach of the on-coming vehicle which is actuating the signal to other approaching vehicles, the lever 11 is provided. A similar lever 11 is provided for each of the windows 10 and inasmuch as they are of identical construction only one of them need be described.

85

90

95

100

This lever as shown in Figure 3 may assume the form of a human hand and arm 12, on one of its lever arms 13 while the other lever arm projects substantially at right angles 5 from the arm 13 making this lever 11 of substantially bell-crank formation. The arm 14 is adapted for an operation which will soon appear. A stop 15 limits the movement of lever 11.

10 For ringing the bell a bell clapper or knocker 16 is provided on each of the sides of the tower facing one of the approaching streets for operation by a vehicle approaching from that street as will be hereinafter 15 more fully described. These knockers or clappers 16 are of identical construction, and it is only necessary to describe one of them. As shown in Figure 2 they are pivoted above the bell at 17 and have the pendulous portion 20 18 for engagement with the bell to give the audible signal.

For operating this bell clapper or knocker 16 into engagement with the bell a lever 19 is provided having a portion 20 for engagement with the knocker 16 and an enlarged portion 21 for engagement with the arm 14 of lever 11, as appears most clearly in Figure 3. It can easily be seen that this lever 19 due to the heavy weighted arm 21 will 25 normally assume the position shown in Figures 2 and 3, the actuating arm 21 thereof being in an elevated position. When the lever 19 is thus placed it projects above the shoulder 22 on the pendulous knocker 16 and 30 in such position is adapted to engage said shoulder to force the knocker 16 about the pivot 17 into engagement with the bell upon downward movement of said arm 20. Suitable brackets 23 or other mounting means 35 may be secured to the tower for mounting the levers 19, as well as the clappers 16.

Each of the above described set of signal actuating means is controlled by identical 40 automatic operating structure provided for actuation by approaching vehicles from each of the several streets leading to the intersection. This actuating means for each of the signal actuation systems comprises a lever 24 integral with the spindle 25 upon which 45 the lever arms 11 are mounted, an elongated rod 26 pivotally secured to said lever at one end at 27 and to a second lever 28 at its opposite end. The lever 11 may be adapted for turning movement by the rod 26 by a 50 direct pivotal connection between said lever 11 and rod 26, the lever 24 being connected or disconnected to the spindle 25. The pivotal connection 25^a interconnects these members through an arcuate slot (not shown) in 55 the wall of the tower, the arcuate formation providing for the movement of said pivot 25^a about pivot 25. If necessary the rod 26 may be cut away as shown at 29 for clearance 60 of the tube or other portions of the lamp signal. The lever 28 may be pivoted at

any desired point but is shown as pivoted to the base of the tower. It can easily be seen that movement of this lever about its pivot 30 will by means of the connecting rod 26 actuate lever 24 or pivot 25^a about pivot 25 and thus move the semaphore signalling arm 11.

For the automatic operation of this lever 28 about its pivot by on-coming vehicles approaching the intersection from the street to 75 which this particular signal actuation system is adapted a swivelly or hingedly mounted platform 31 is placed in the bed of the street. The platforms 31 may be positioned wherever desired or found necessary relative to the intersection when the preferred embodiment is placed at a distance substantially twenty feet from said intersection. This hingedly mounted platform as appears most clearly in Figure 9 may consist merely of a surface 80 large enough to support an on-coming vehicle, and is supported itself upon a surface of the street, as shown at 32, and upon part of the actuated mechanism 33 by means of a support 34. As also appears most clearly in Figure 9 this support 34 is adapted to turn the member 33 about its pivot 35 upon the exertion on said platform 31 of a force which may be caused by gravity acting on the passing vehicle.

95 This member 33 transmits its movement to the lever 28 by means of the flexible connector 36 secured to the member 33 by the fastening hook 37 and connected to the lever 28 as shown at 38. A pipe or other conduit means, 100 such as that shown at 39 may be utilized to assure free movement of the flexible connector 36.

The stationarily positioned signalling arrows 40 are placed adjacent each of the platforms 31 upon the sidewalks or in any other 105 positions as desired to indicate to on-coming vehicle operators the presence of said platform. This is to assure warning to the driver of on-coming vehicles that the intersection is 110 equipped with the device. This arrow 40 may be made adjustable so as to point to different places to accommodate variable positions of the platform 31.

In order to warn the transverse pedestrian traffic of the approach of the on-coming vehicle actuating signal, the signal means indicated by the numeral 5 as heretofore set forth is provided. This signal means 5 is adapted for actuation by the platform 31 to assure 115 operation thereof simultaneously with the actuation of the vehicle traffic signal.

120 This is accomplished by mounting a lever 41 similar in form and operation to the member 33 for actuation by the downwardly projecting support 34, as shown in Figure 8. This member 41 is adapted to actuate the 125 pedestrian signal semaphore to operative positions as shown in Figure 8 and to inoperative position, by means of the flexible con-

nection 43 interconnecting said member 41 and the actuating arm 44 of said signal 42. A hook member 45 similar in formation and function to the member 37 is provided for the connection of the flexible member 43 to the lever 41 while a rigid member 46 swivelly mounted upon the actuating arm 44 of the semaphore 42 connects the other end of the flexible member 43 to the signal 42. 5 The flexible member 43 may be suitably housed by the tubing 46^a which may be of a form similar to the tubing 39. This signal 42 may be mounted on any desired means such as a post or pillow 47 which may be positioned at any desired point to give the signal to the best advantage and which is shown as positioned adjacent the transverse cross walk which intersects the path of the approaching vehicle. When the semaphore 42 is 10 thrown downwardly about its pivot 48 to the inoperative position it is housed or shielded in the pocket 49, which may be secured on the post 47 by any suitable fasteners 50. This semaphore signal may be provided with any 15 desired signal such as "Stop". This actuating means is provided for each of the pedestrian traffic signals 5 for connection with each of the platforms 31 as in the case of the means for actuation of the vehicle traffic 20 signals of the tower 4.

From the foregoing description, the use and operation of my device is easily understood. Upon the approach of a vehicle to the intersection along any of the streets leading 25 to said intersection, the operator of said vehicle is apprised of the existence of the signal system by the arrow 40 provided adjacent that particular street at the approach to the corner. This enables him to drive his 30 vehicle upon the platform 31 for purposes of actuating the signal.

This action depresses the platform 31 under the force of gravity and rotates the members 33 and 41 about their pivots.

45 In the case of the rotation of the member 33 about its pivot the flexible member 36 is placed under tension and rotates the lever 28 about its pivot 30. This operation, by means of the interconnecting rod 26, rotates the lever 50 24 or pivot 25^a about the spindle 25 and raising the semaphore signalling arm 11, to the position shown in Figure 3.

When the semaphore signal arm is thus raised to the position shown in Figure 2 the 55 hand 12 thereof will point in the direction of the vehicle operating the signal as shown most clearly in said figure indicating to any vehicle which may happen to be approaching from the right or left of the vehicle which is 60 actuating the signal that said actuating vehicle is approaching the intersection from its specific direction. The elevation of the hand 12 of course uncovers the window 10 and thus permits visibility of the signal lamp 65 7 which may be colored red or in any other

suitable warning color, to the operator of any vehicle which may be approaching and for which the signal is intended.

This actuation of the semaphore signal lever 11 upwardly also elevates the end 14 or lever 11 actuating lever 19 and depressing the arm 20 thereof. This operation brings about engagement of said arm 20 with the knocker 16 at the shoulder 22 thereof thus forcing the knocker 16 inwardly and into engagement 70 with the bell, to give an audible signal to any on-coming vehicle.

In the case of the actuation of the lever 41 pedestrian traffic semaphore signal member 42 is raised from its pocket 49 to the position shown in Figure 2 and Figure 8 in a manner easily understood, thus warning pedestrians 80 of the approach of the actuating vehicle.

Upon the passage of the vehicle from the platform 31 the particular signals in the signal tower 4 and on the post 47 controlled by the particular platform 31 which the vehicle has passed to the inoperative position under the force of gravity acting on the said members. The platform 31 will be returned 85 to its elevated position under the force exerted by these members or the force exerted by its portion 31^a which may be constructed of spring material or the force of springs (not shown) which may be placed there- 90 beneath or in engagement therewith for purposes of elevation of said platform. The apparatus is then in place for a repetition of the operation.

The semaphore signal arm 11 on the tower 100 is visible to all transverse traffic as can easily be seen from an examination of Figure 2 inasmuch as it extends outwardly from the side of the signalling tower where it may be seen by transverse traffic coming in either direction, thus warning vehicles coming from either way that an approaching vehicle has the right of way and will shortly cross their path.

It can thus be easily seen that a vehicle 105 upon approaching an intersection will delay the actuation of his signal and its passage into the intersection if a semaphore signal arm 11 indicates an approach of a vehicle from either his right or his left.

Inasmuch as the laws throughout the land 110 are uniform in that the vehicle approaching from the right has the right of way, the signalling system provides for signalling to the right to forestall said assumption of the right of way by a vehicle approaching from the right if the vehicle approaching from the left actuates the signal first. It is in the scope of my invention, however, to arrange the semaphore levers 11 to point in any desired direction. The pedestrian traffic signals may be 115 so placed relative to the platforms 31 that ample warning is given pedestrians approaching the street. If desired the platform 31 could be placed in a zone indicated at 50 120 125 130

of a width sufficient only to accommodate the passage of one car therethrough thereby assuring actuation of the pedestrian traffic signal in time to prevent entry of said pedestrian into said zone 50. This will cause approaching automobiles to slow down at the intersection for passage therethrough, thereby adding to the safety of said passage.

It is thus seen that I have provided a traffic signalling system which is adapted for simultaneously signalling transverse vehicles as well as pedestrian traffic of the approach of a vehicle and which by the use of restricted zones entails upon the operator of the actuating vehicle procedure with caution through that intersection, thereby adding to the safety and comfort of traffic passing through and about said intersection.

I claim:

20 1. In a traffic signalling system, a separate pedestrian control signal, a separate vehicle control system, means interconnecting said control signal and control system and means for automatically operating said signals upon the approach of a vehicle.

25 2. In a traffic signalling system, a separate pedestrian control signal, a separate vehicle control signal, and means for automatically operating said pedestrian signal and said vehicle control signal upon the approach of a vehicle, comprising a platform positioned in the path of said vehicle for movement by said vehicle and means interconnecting said platform and said pedestrian signal and said vehicle control signal for the transmission of said movement to said signals.

30 3. In a signalling system for directing traffic and the like, a signalling tower adapted for positioning at the intersection of streets to signal transverse traffic, a platform positioned in the path of an approaching vehicle and adapted for the actuation of the signals of said signal tower, and means positioned adjacent said platform for indicating the presence of said platform to the on-coming vehicle.

35 4. A traffic controlling system comprising in combination a separate pedestrian control signal, a separate vehicle control system, means connecting said pedestrian control signal and said vehicle control system for simultaneous operation upon actuation of said vehicle control system; and means for sounding an audible signal upon actuation of said control signal and vehicle control system.

40 5. A traffic signal comprising a signal post, a plurality of signal members swingably mounted thereon, said signal members having an integral arm extended at right angles thereto, a bell mounted upon said post, a plurality of bell clappers, a rockable lever associated with each bell clapper, and said levers projecting into the path of respective arms of said signal members whereby opera-

tion of said signal members said bell will be struck.

5 6. A traffic signal comprising a hollow signal post having a plurality of signal windows, a source of illumination interiorly of said post to illuminate said windows, a plurality of signal members swingably mounted upon the exterior of said post, one of said signal members being associated with each window and normally disposed thereover, each of said signal members having an integral arm extended at right angles thereto, a bell mounted within said post, a plurality of bell clappers rockably mounted upon said post and adapted to strike said bell, a rockable lever connected to respective bell clappers, and said levers projecting into the path of respective arms of said signal members, whereby operation of said signal members said signal windows will be displayed and said bell will be struck.
